Primary Examiner — Robert M Spear*Assistant Examiner* — Kendra L Hamilton(74) *Attorney, Agent, or Firm* — McGuireWoods LLP(57) **CLAIM**

I claim the ornamental design for a chainsaw, as shown and described.

DESCRIPTION

FIG. 1 is a right perspective view of the chainsaw;
FIG. 2 is a front view of the chainsaw shown in FIG. 1;
FIG. 3 is a rear view of the chainsaw shown in FIG. 1;
FIG. 4 is a left side view of the chainsaw shown in FIG. 1;
FIG. 5 is a right side view of the chainsaw shown in FIG. 1;
FIG. 6 is a top view of the chainsaw shown in FIG. 1; and,
FIG. 7 is a bottom view of the chainsaw shown in FIG. 1.
The portions of the figures shown in broken lines depict
environmental structure that forms no part of the claimed
design.
